UNITED STATES PATENT OFFICE

2,015,090

MANUFACTURE OF SHOE UPPERS

Harold L. Sawyer, Lynn, Mass., assignor to United
Shoe Machinery Corporation, Paterson, N. J.,
a corporation of New Jersey

Application June 12, 1933, Serial No. 675,375

13 Claims. (Cl. 12—146)

This invention relates to shoe uppers and to methods of preparing shoe uppers for the operation of assembling them upon their lasts.

Objects of this invention are to prevent the formation of wrinkles in the lining of a shoe upper prior to and during the lasting operation and so to prepare the upper that, after it is lasted and the last is removed, the upper and lining will adhere together, will have the plump feel characteristic of a shoe upper containing a doubler and will have desirable shape-retaining characteristics such that when dented it will promptly snap back to the shape imparted to it in the lasting operation.

With these objects in view, the invention, in one aspect, consists in a method of treating lined shoe uppers prior to assembling them upon their lasts which comprises imparting a preliminary shape to the shoe upper approximating that which it is to have in the finished shoe and subjecting the lined upper while so shaped to heat and pressure to activate thermoplastic adhesive located between the upper and lining.

Preferably the lining material employed will be a woven napped fabric having upon the outer portions of the nap fibers minute, discrete particles of thermoplastic adhesive, such lining being employed at least in the vamp portion of the shoe. Treatment by the present method of a shoe upper having a vamp lining of the character just described results in a shoe upper prepared for assembling upon its last which is shaped, at least transversely, approximately to the form which it is to have in the completed shoe and which has the outer portions of the fibers of the nap anchored to the inner surface of the outer (or leather) layer of the upper. In another aspect invention is to be recognized in a shoe upper so prepared.

As herein disclosed, the treatment of the shoe upper is applied to that portion of the vamp and quarter which lies between the tip line and the ball line or forward end of the shank, though this, it should be understood, is merely for purposes of illustration and is not to be taken as limiting the scope of the invention to the treatment of that part of the shoe. A heated form or mold is provided over which a closed shoe upper may be placed, the form supporting the inner surface of the lining in the region indicated and being approximately of the shape which this part of the upper will have to assume in the completed shoe. Cooperating with the heated form is a presser member which engages the outer surface of the upper in the region supported by the in-

ner form and is operated to press the upper against the heated inner form to cause adhesion between the nap of the lining and the inner surface of the upper.

In the drawings,

Fig. 1 is a perspective view of a shoe upper and lining before it is treated in accordance with the method of the present invention;

Fig. 2 is a perspective, somewhat diagrammatic view of apparatus adapted for use in practising the method of the present invention;

Fig. 3 is a perspective view of a shoe upper after it has been treated by the method of the present invention and its vamp portion has been shaped approximately to its final form and its upper and lining have been caused to adhere to each other; and

Fig. 4 is a sectional view showing an electrically heated form over which the upper is shaped and a cooperating yielding presser member utilized for shaping the upper to the form.

In practising the method of the present invention, as illustrated herein, an upper is first prepared as shown in Fig. 1, the upper comprising a vamp 10, a quarter 12, a vamp lining 14 and a quarter lining 16. The vamp lining 14 at least of the shoe upper consists of a woven, napped fabric, the napped surface 18 of which is disposed adjacent to the inner face of the vamp 10 and has on the outer portions of the fibers 20 of the nap minute, discrete particles 20 of thermoplastic adhesive. The lining material may be that disclosed in Letters Patent of the United States No. 1,931,612, granted October 24, 1933, in the name of Henry Kahlmeyer.

As illustrated, the upper is closed by a back seam 22 and at the throat may be held by the usual lacing 24.

An upper thus prepared is placed over an inner mold 26 (Fig. 2) which is preferably heated, for example by an electric heating unit 28 (Fig. 4). The form 26 preferably extends from approximately the tip line of the vamp to the beginning of the shank or waist portion of the upper and has a contoured external upper and outer surface approximating the shape of the portion of a shoe last from the tip line to the shank to which the shoe upper will ultimately be lasted. The form 26 may conveniently have the shape of one half of a truncated cone, preferably with a hump at 30 where it engages the throat portion of the vamp.

The presser member which cooperates with the heated form 26 is indicated at 32 in Fig. 2 and comprises an outer metallic shell having an inner

face complementary to the shape of the form 26 and padded, as illustrated at 34, to provide yielding means for pressing the shoe upper against the form 26. The pad 34 may consist of a thick 5 layer of felt secured to the presser member 32 so that, when the presser member 32 is moved toward the form 26 with the upper and lining between them, the padding 34 will cause a yielding pressure to be applied to the upper and lining 10 to shape them to the heated form 26 and to press them together while heat from the form 26 will penetrate the lining and cause the minute, discrete particles of thermoplastic adhesive adhering to the nap thereof to soften or melt, thereby 15 causing the nap to stick to the inner surface of the upper leather. Preferably the presser member 32 is cut away or notched as at 35 to avoid pressure upon the throat portion of the upper in the region where the lacing of a laced 20 upper would be located. Thus, the pressure is concentrated at the sides of the vamp and across the ball portion of the vamp at the rear of the tip line.

The form 32 may be supported and operated in 25 any convenient manner to press it against the form 26 and release it therefrom and, as illustrated, the form 32 is provided with a pair of lugs 38 which are pivoted by pins 36 to a pair of arms 40 which, in turn, are pivoted to supports 42 rising from a bed plate 44 on which the forms 26 30 are mounted. Any convenient means, for example a treadle, may be provided to swing the arms 40 downwardly to cause the presser member 32 to press the upper upon the form, and springs 35 46 may be provided to maintain the presser member 32 normally in raised position. The pivots 38 enable uniform pressure to be applied by the presser member longitudinally of the form. Preferably, and as shown in Fig. 2, two of the heated 40 forms 26, with the corresponding pressure-applying forms 32, are arranged for alternate operation, one of them remaining in operative relation to a shoe upper while a work-piece is being removed from and another work-piece applied to 45 the other.

The shoe upper prepared in accordance with 50 the present invention is ready for the assembling operation. The placing of the last therein is facilitated by reason of the preshaping of the upper approximately to the shape of the last, and the operations of pulling-over and lasting the upper are also facilitated because the upper and lining can be treated as a unit and no time or effort need be expended in preliminary adjustment of the lining relatively to the upper. Such 55 relative movement between the upper and lining as is necessary to complete the shaping of the preshaped upper to its last is permitted since the lining is not rigidly secured to the upper but is anchored or tethered thereto by the nap fibers, the outer ends only of which are secured to the outer or leather layer. Consequently, when the 60 shoe is completed and the last withdrawn, it is found that the lining is entirely free of wrinkles, and imparts to the upper the plump feel desired by shoemakers, and also imparts thereto a considerable amount of resiliency so that as the upper is pushed in or dented it tends promptly 65 to resume the shape given to it by the lasting operation.

Having thus described my invention, what I claim as new and desire to secure by Letters Patent of the United States is:

1. That improvement in methods of preparing

a closed shoe upper for the operation of assembly upon its last which consists in imparting to the forepart of a lined shoe upper having inactive cement between the layers of the upper a shape approximating that which it is to have 5 in the completed shoe, and subjecting the upper while so shaped to heat and pressure thereby activating the cement and securing the lining and upper together.

2. That improvement in methods of preparing 10 that portion of a closed and lined shoe upper which is to be lasted for the operation of assembly upon its last which consists in imparting to the forepart of the lining and upper having cement between the outer layer of the upper and the 15 lining a shape approximating that which it is to have in the completed shoe, and subjecting the upper while so shaped to yielding pressure and the lining to heat thereby activating the cement between the layers. 20

3. That improvement in methods of preparing a closed shoe upper for the operation of assembly upon its last which consists in placing the forepart of a lined shoe upper having inactive thermoplastic cement between its outer layer and its 25 lining over a heated convex form, and yieldingly pressing the upper against the heated form thereby activating the cement by heat transmitted through the lining and securing the layers of the upper together. 30

4. That improvement in methods of preparing a closed shoe upper for the operation of assembly upon its last which consists in embodying in a shoe upper a napped lining having minute, discrete particles of thermoplastic adhesive on the 35 end portions of the nap adjacent to another layer of the upper, shaping the forepart of the upper approximately to the curvature it is to assume in the completed shoe, and subjecting the upper while so shaped to heat and pressure thereby activating the adhesive and causing adhesion of the nap to the contacting layer of the upper. 40

5. That improvement in methods of preparing a closed shoe upper for the operation of assembly upon its last which consists in imparting to the forepart of a lined shoe upper having thermoplastic cement between its layers a preliminary transverse curvature approximating but less than that which the upper will have in the completed shoe, and subjecting the upper while so shaped to heat and pressure thereby activating the cement between the upper and lining. 45

6. That improvement in methods of preparing a closed shoe upper for the operation of assembly upon its last which consists in applying 55 to the forepart of a lined shoe upper having thermoplastic cement between its lining and an adjacent layer a transverse curvature less than that which it is to have in the completed shoe, and subjecting the upper while so shaped to yielding 60 pressure and the lining to heat thereby activating the cement between the layers.

7. That improvement in methods of preparing a closed shoe upper for the operation of assembly upon its last which consists in embodying in 65 a shoe upper a napped lining having minute, discrete particles of thermoplastic adhesive on the end portions only of the nap fibers, shaping the upper to a transverse curvature less than that which it will have to assume in the completed 70 shoe, and subjecting the upper while so shaped to heat and pressure to effect activation of the adhesive and cause adhesion of the nap fibers to the adjacent layer of the upper. 75

8. That improvement in methods of preparing

- a closed shoe upper for the operation of assembly upon its last which consists in applying the forepart of a lined shoe upper having thermoplastic cement between its lining and the adjacent layer 5 to a heated form having a transverse curvature less than that which the upper is to assume in the completed shoe, and subjecting the upper while so shaped to pressure to cause adhesion between the lining and upper.
- 10 9. That improvement in methods of preparing a closed shoe upper for the operation of assembly upon its last which consists in embodying in a shoe upper a woven, napped lining having minute, discrete particles of thermoplastic adhesive on the 15 end portions only of the nap, shaping the forepart of the upper to a transverse curvature less than that which it is to assume in the completed shoe, and subjecting the upper while so shaped to heat and pressure thereby activating the adhesive and causing adhesion of the nap to the adjacent layer of the upper.
10. That improvement in methods of preparing a closed shoe upper for the operation of assembly upon its last which consists in disposing the forepart of a lined shoe upper having thermoplastic cement between the upper and lining over a form having a circular transverse curvature, shaping the upper to the form, and subjecting the upper while so shaped to heat and pressure to ac- 20 tivate the cement between the lining and upper.
11. That improvement in methods of preparing a closed shoe upper for the operation of assembly upon its last which consists in disposing the forepart of a lined shoe upper having thermoplastic cement between the upper and lining over a form with the lining next to the form, said form having a circular transverse curvature approximate to but less than that which the upper will have in the completed shoe, pressing the upper against the form to shape it to the form, and subjecting the upper while so shaped to heat to activate the cement between the upper and lining. 25
12. As a step product, a closed unlasted shoe upper comprising an inner layer of fabric and an outer layer, the inner layer being adhesively secured to the inner face of the outer layer and the forepart at least of the upper being molded transversely to approximately the shape it will have in the completed shoe. 20
13. As a step product, a closed shoe upper comprising an inner layer of woven, napped fabric and an outer layer, the end portions of the fibers of the nap being secured to the inner face of the outer layer at the forepart and the upper being 25 molded transversely to approximately the shape it will have in the completed shoe.

HAROLD L. SAWYER.
